UNITED STATES PATENT OFFICE.

ROBERT M. DOWNIE, OF ALLEGHENY, PENNSYLVANIA.

PORTABLE DRILLING-MACHINE FOR OIL-WELLS, &c.

SPECIFICATION forming part of Letters Patent No. 251,841, dated January 3, 1882.

Application filed November 25, 1881. (No model.)

To all whom it may concern:

Be it known that I, ROBERT M. DOWNIE, a citizen of the United States of America, residing at Allegheny, in the county of Allegheny and State of Pennsylvania, have invented certain new and useful Improvements in Portable Drilling-Machines for Oil-Wells, &c.; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to portable drilling-machines, and is an improvement on my former invention, for which a patent was granted me by the United States, bearing date of June 15, 1880, No. 228,737; and it consists in the introduction of new parts and in a slight change of others, whereby the machine is made more effective, as will be fully described hereinafter.

The accompanying drawings represent my invention.

Figure 1 is a side elevation of my invention. Fig. 2 is a plan view of the same.

The frame A, with all that pertains to the machine, including steam-engine and boiler, is placed upon wheels, and may be transported from place to place in its entirety.

The spring-pole described in my former patent I discard and substitute therefor a rigid walking-beam, *a*, of which the rear end is pivoted on top of the post K, its middle sliding up or down in guides upon the post J. The elasticity lost in the exchange of a rigid beam for a spring-pole is compensated by a spring at the bottom of a tube placed under the beam *a* in front or near the post J, in which tube is a plunger resting on the spring. A rod on the plunger bears against the under side of the beam and assists by the reaction of the spring in elevating the beam after each descent.

At the front of the frame A are bearings B, on which is journaled the cable-reel *f*, having on one of its ends the cog-wheel C. In front of the reel *f* is another smaller one, *i*, which carries the sand-pump rope. At the side op-

posite to the wheel C on the shaft of the reel *i* is a small friction-wheel, *n*, that is journaled in a sliding box, L, operated by the lever O. By means of this lever the friction-wheel *n* 55 can be brought in contact with a flange, Q, on the rim of the driving-wheel R, and when in contact turns the reel *i*.

Foremost on the bearings B is the shaft of the driving-wheel R, with the cog-wheel S on 60 its other end. The wheel S is provided with a wrist-pin, *l*, to which the rod T is attached, that forms the connecting-link between the wheel S and the beam *a*, to which it imparts its motion. At the extreme forward end of the 65 beam is suspended a temper-screw, to which the cable that bears the drilling-tool is attached.

Between the cog-wheels S and C, at the side of the frame A, is introduced the smaller cog-wheel M, by which a connection between the driving-wheel R and the cable-reel *f* is established. This wheel M, when the reel is not in use, is thrown out of gear, when the wheels S and C cease to act together.

The changes made in this improvement, differing from my former invention, consist in the beam *a* and in wheels S and C, they being here provided with cogs. The addition of the wheel M to better control the cable-reel *f* 80 and the tube *p*, with its spring and plunger, are made to facilitate the working of the machine. This and the whole machine being placed in one frame upon wheels, thus allowing the machine to be moved and operated 85 without dismounting or disconnecting any of its parts, constitutes the improvement.

Having thus described my invention, I claim—

1. In a portable drilling-machine, the combination of the reel *f* and cog-wheels S, C, and *m* with the driving-wheel R, as shown and described.

2. In a portable drilling-machine, the combination of the driving-wheel R, wheel S, rod T, beam *a*, and tube *p*, arranged as set forth.

In testimony whereof I affix my signature in presence of two witnesses.

R. M. DOWNIE.
